(57) **CLAIM**

The ornamental design for dispensing package, as shown and described.

DESCRIPTION

FIG. 1 is a top plan view of a first embodiment of a dispensing package embodying our new design;

FIG. 2 is a right side elevational view thereof;

FIG. 3 is a front elevational view thereof;

FIG. 4 is a left side elevational view thereof;

FIG. 5 is a bottom plan view thereof;

FIG. 6 is a back elevational view thereof;

FIG. 7 is a top plan view of a second embodiment of the dispensing package;

FIG. 8 is a right side elevational view thereof;

FIG. 9 is a front elevational view thereof;

FIG. 10 is a left side elevational view thereof;

FIG. 11 is a bottom plan view thereof; and,

FIG. 12 is a back elevational view thereof.

The shading disclosed within the drawings is meant to represent color contrast.
